DEMOUNTABLE TOP FOR PRESSING MACHINES

George C. Ricketson, New York, N. Y.

Application December 31, 1936, Serial No. 118,475

5 Claims. (Cl. 38—66)

This invention relates to attachments for pressing machines, and particularly to a removable top and pad for the bucks of pressing machines used in pressing shirts and other articles, an object being to provide a construction whereby a top and pad carried thereby may be quickly applied or removed at any time.

Another object is to provide a top for the bucks of pressing machines which is formed of metal and with various parts for receiving a pad so that when the top is slid into position the pad will also be slid into operative position.

An additional object is to provide a demountable metal top for the bucks of pressing machines wherein there is presented a metal body more or less arc-shaped and formed with turned-over ends forming grooves adapted to receive the lower edges of a buck when the top is slid into position.

20 In the accompanying drawings:

Fig. 1 is a perspective view showing a part of a pressing machine ready to receive the tops forming the invention;

Fig. 2 is a perspective view of a collar top adapted to be used on the central buck shown in Fig. 1;

Fig. 3 is a side view of the collar buck shown in Fig. 1 with a top and pad mounted thereon;

Fig. 4 is a view similar to Fig. 3, except that 30 a cuff buck with a top and pad is disclosed;

Fig. 5 is an enlarged front view of one of the cuff bucks shown in Fig. 1;

Fig. 6 is an edge view of the structure shown in Fig. 1, certain portions being broken away;

35 Fig. 7 is a detail fragmentary perspective view on an enlarged scale of part of one edge of the buck shown in Fig. 5, said view illustrating how the retaining pins are mounted.

Referring to the accompanying drawings by 40 numerals, 1 indicates a pressing machine of any desired type, as for instance the type shown in Patent No. 2,059,295. The machine 1 is provided with lower bucks 2 and upper bucks 3. The upper bucks 3 are always heated and sometimes the 45 lower bucks 2 are also heated, although in many cases they are left unheated. The particular construction and arrangement of the respective bucks form no part of the present invention. However, it is to be noted that on the various 50 lower bucks padding is used when the machine is in use. Heretofore this padding was applied directly to the bucks and when the same became filled with starch or other matter it was necessary to stop the machine and rather laboriously 55 remove the old padding and apply new padding.

This required quite an appreciable time and therefore was more or less objectionable.

In the present invention means have been provided whereby the padding used on the bucks may be quickly applied and removed at any time 5 so that the pressing machine is substantially never out of operation. In order to secure these desired results there have been provided metal members known as demountable tops, and on these metal members have been arranged suitable 10 padding. The tops may be slid into position at any time on to the bucks and also may be slid off of the bucks at any time.

As shown in Fig. 2, the top 4 is of sheet metal and is substantially arc-shaped. A yoke extension 5 is also provided. It will be noted that the body of the top 4 is bent at the respective ends so as to present inwardly facing channels 6 and 7 whereby the device may slide on the lower end edges of the collar buck 8. The cuff top 9 20 is identical with the top 4, except that it is shaped to fit the respective cuff bucks 10 and 11. Also the extension 5 is not provided on the top 9. The top 9 is preferably of a size to completely fit the top of the buck 10 or 11, while the top 25 4 is substantially half as wide as buck 8.

In pressing machines of this kind only the front half of the respective pads is used, and consequently it is only necessary to make the top 4 and the pad carried thereby half the width of 30 buck 8. The top 9, however, and the pad carried thereby are the full width of the respective bucks 10 and 11. When the tops are mounted in position, as shown in Fig. 5, they may be used until the front half becomes unusable by 35 reason of the deposit of starch. The tops with their pads are then slid off, reversed, and slid back into position so that the rear half is now the front half and the machine may then be used in the usual manner.

The top 9 is formed with an abutment 13 which is riveted, welded, or otherwise rigidly secured in place. It will be noted that there is an abutment 13 at each end of the top 9 so as to limit the pad 14. Pad 14 may be of any desired kind. 45 It has been found desirable to provide a coarse body 15 of felt, waste, or other padding material. On top of this body is arranged preferably two layers of fabric 16 which may be cotton, wool, or the like. On top of the layer 16 the covering 50 layer 17 of muslin or other fabric is provided and forms a finishing cover which is held in place by the respective rows of pins 18 and 19 carried by the respective removable bars or holders 20. Each bar 20, as shown in Fig. 7, is provided with 55

a recess 21 for receiving the head 22 of the respective pins. These pins are preferably bent downwardly so that there will be no tendency of the covering 17 slipping off. The bar 20 may be 5 wood, metal, "Bakelite," or other material, and is slidably mounted in a holding plate 23 which has inturned edges 24 and 25 forming facing grooves.

The plate 23 may be riveted or otherwise rigidly secured to the abutment 13 so as to form a part 10 of the top. As clearly shown in Fig. 5, the buck 10 is provided with overhanging end members 10' which are received in the respective channels 6 and 7 whereby the top may be slidably mounted 15 in place. Suitable handholds 26 and 27 are secured to the inturned ends forming the channels 6 and 7 whereby the top may be manipulated when applying or removing.

In order to lock or hold the top 9 in place, the 20 buck 10 is provided with notches 28 and 29 in each end. The turned-in ends of the top 9 carry springs 30, as shown in Fig. 6. One end of these 25 springs is riveted to the top 9, while the other end is formed with a V-shaped part 31 projecting through an opening 32 whereby the part or catch 31 may snap into one of the notches 28 or 29. When the top 10 is in one position on the buck, member 31 will be in the respective notches 28, but when the top is removed and reversed, the 30 catch 31 will snap into the other notch 28 on the respective sides.

It will be understood that the description of buck 10 and top 9 and associated parts apply to buck 11. Also it will be understood that the construction of top 4 is identical with top 9, except that it fits the buck 8 and is provided with the yoke extension 5 for ironing the yoke of an ordinary shirt while the collar is being pressed in the regular way. The respective ends of the top 40 4 are made identical with that shown in Fig. 5 and therefore will need no additional description. However, the yoke extension 5 is slightly different in that the respective sides 33 and the end 34 are bent down so as to receive the respective plates 45 23. These plates and associated parts function as illustrated in Figs. 5 and 7.

The cover 17 used on the pad mounted on top 4 will have the respective ends engage the pins in the plates 23 at the respective sides and the side 50 of the cover moved over end 34 so as to engage the pins carried by plate 23. This arrangement maintains the cover taut over the entire padding. It is to be noted that in Fig. 2 the padding has been omitted, but when applied it will be identical 55 with that shown in Fig. 5, except for the part that extends over the yoke extension 5. In Fig. 3 it will be observed that the cover 17 has the part 35 engaging the pins on the end plate 23. Also it will be noted from Fig. 3 that the top and the pad 60 14' carried thereby only cover approximately half of the buck 8. In Fig. 4 the pad 14 covers the entire buck, as described in respect to Fig. 5.

The catch 31 acts as a lock for locking the 65 respective tops and the pads carried thereby in the desired operative position, but by a strong pull on the handholds 26 and 27 catches 31 will move out and permit the top and its pad to be removed. When the top is reversed and forced back into

position, the catch 31 will naturally slip into the notches 29 and thereby temporarily lock the top and pad in position.

It is, of course, understood that other forms 5 of locks or means for holding the top in position could be used without departing from the spirit of the invention. Also other forms for holding the cover 17 could be used, but it has been found desirable to use the pins 18 as shown in Fig. 7 because it is easy to remove any injured pin and 10 supply a new one. It will be understood that the bar 21 is held frictionally in position and may be slid out at any time after the top cover 17 has been removed.

I claim:

1. A metallic top for pressing machines comprising an arc-shaped body, an abutment secured to each end of said body and upstanding therefrom for preventing a padding moving off the ends of the body, a plate having facing grooves 20 mounted on each of said end abutments, and a covering cloth holder carried by said plates.

2. A top for the buck of a pressing machine comprising a metallic arc-shaped body adapted to support an arc-shaped head, an abutment carried by said body at each end thereof, a holding plate rigidly secured to each of said abutments, each of said holding plates having on opposite edges turned-over members forming facing grooves, and a pad holder carried by each of said 30 holding plates, each of said pad holders comprising a body slidably mounted in said grooves, and removable pins extending through part of said pad holders and in a direction away from the abutment.

3. A top for the buck of a pressing machine provided with notches in the ends of the buck comprising an arc-shaped metallic body having at each end turned-in parts forming inwardly facing grooves adapted to fit over the lower edges 40 of said buck when the top is in operative position, means carried by the end portions of said top interlocking with said notches for holding in position said top, and means carried by the ends of said top acting to hold a pad on said top.

4. A metallic top for the buck of a pressing machine comprising an arc-shaped body having inturned ends forming channel members for slidably fitting over the lower ends of said buck, means carried by said body for securing a pad thereto, and handholds carried at said inturned ends presenting members adapted to be used when applying and removing said body.

5. A metallic top for the buck of a pressing machine comprising a substantially arc-shaped body 55 slidably and removably mounted on the buck, said body at its respective ends being formed with inwardly facing channels slidably fitted over the respective edges of said buck for preventing removal of the top except by a sliding motion, said top being adapted to be slid off said buck, reversed and then slid back on the buck, means at each end of said body interlocking with said buck for preventing accidental shifting of the top while on the buck, and means for holding a pad on said 60 body.

GEORGE C. RICKETSON.
